[57] CLAIM

The ornamental design for a wall lamp, substantially as
shown and described.

DESCRIPTION

FIG. 1 is a side elevational view of a wall lamp showing
my new design;

FIG. 2 is a top plan view thereof;

FIG. 3 is a front elevational view thereof;

FIG. 4 is a rear elevation view thereof;

FIG. 5 is a bottom plan view thereof;

FIG. 6 is a side elevational view of a second embodiment
of my new design;

FIG. 7 is a top plan view of the embodiment showing in
FIG. 6;

FIG. 8 is a front elevational view of the embodiment
shown in FIG. 6;

FIG. 9 is a perspective view of the embodiment shown
in FIGS. 1 through 5 on an enlarged scale.
